(57) **CLAIM**

The ornamental design for the light globe with internal optic, as shown and described.

DESCRIPTION

FIG. 1 is a perspective view from above of the light globe with internal optic in accordance with my design, illustrated in a clear glass embodiment;

FIG. 2 is a perspective view from above of the light globe with internal optic in accordance with my design illustrated in a frosted glass embodiment;

FIG. 3 is a top plan view of the light globe with internal optic in accordance with my design;

FIG. 4 is a side elevation view of the light globe with internal optic in accordance with my design;

FIG. 5 is a bottom plan view of the light globe with internal optic in accordance with my design; and,

FIG. 6 is a cross section plan view taken through FIG. 4, of the light globe with internal optic in accordance with my design.

The light globe of the present invention is symmetrical from the side elevational views.

The invention is illustrated in a clear glass embodiment in FIGS. 1, 3, 4, 5, and 6 and in a frosted glass embodiment in FIG. 2.

The light globe of the present invention includes a smooth or frosted exterior surface and a dimpled optical design on the interior.

With the exception of the frosted glass, all other views of the second embodiment are identical to the first embodiment.
